(57) **CLAIM**

The ornamental design for a dental floss holder as shown and described.

DESCRIPTION

1. Dental floss holder

1.1: Perspective

1.2: Front

1.3: Back

1.4: Left

1.5: Right

1.6: Top

1.7: Bottom

The thicker lines define the external overall shape and the thinner lines represent contours and do not illustrate ornamentation or decoration on the surface of the device.
